UNITED STATES PATENT OFFICE.

ERNEST H. SCHWEERING, OF KANSAS CITY, MISSOURI.

DESIGN FOR A SPARK-PLUG EXTENSION.

59,686.

Specification for Design.

Patented Nov. 15, 1921.

Application filed June 27, 1921. Serial No. 480,940. Term of patent 3½ years.

To all whom it may concern:

Be it known that I, ERNEST H. SCHWEERING, a citizen of the United States, residing at Kansas City, Jackson county, Missouri, have invented a new, original, and ornamental Design for a Spark-Plug Extension, of which the following is a specification, reference being had to the accompanying drawing, forming a part thereof.

In the drawing:

Figure 1 is a perspective view of a spark plug extension, showing my new design.

Fig. 2 is a bottom plan view of the same.

Fig. 3 is a side elevation of the same.

I claim:

The ornamental design for a spark plug extension, as shown.

ERNEST H. SCHWEERING.
